DESIGN FOR A SLACKS

Walter Falkenstein, Miami, Fla.

Application February 16, 1940, Serial No. 90,299

Term of patent 3½ years

To all whom it may concern:

Be it known that I, Walter Falkenstein, a citizen of the United States of America, residing in the city of Miami, county of Dade, and State of Florida, have invented a new, original, and ornamental Design for a Slacks, of which the following is a specification, reference being had to the accompanying drawing, forming part thereof.

Fig. 1 is a front view of a slacks showing my new design.

Fig. 2 is a rear view thereof.

The characteristic feature of my design resides in the combination, on the specific one-piece slacks disclosed, of the specific appliquéd breast pocket in association with the gathered belt casing and the stitched cuffs as shown.

I claim:

The ornamental design for a slacks, substantially as shown and described.

WALTER FALKENSTEIN.
